AUTOMATIC TILE PRESSES

Franz Dubois and Felix Engmann, Aachen, Germany, assignors to Dubois & Co., Aachen, Germany, a firm

Application December 29, 1952, Serial No. 328,462

Claims priority, application Germany December 29, 1951

3 Claims. (Cl. 25—42)

The present invention relates to presses for the manufacture of wall, floor, and other tiles, and in particular to the design and motion of the tile lifting and filling means for such presses.

With the hitherto known presses, these devices generally operate by jerks, thus causing considerable breakage among the pressed tiles. It is moreover difficult to perform such settings and adjustments of the aforesaid devices as are required for altering the filling space capacity.

Presses of the known designs are objectionable particularly with regard to the arrangement and motion of their tile lifting means, which on the one hand operates in a direct manner whereby the pressed tile, while the ram carrying the upper die is raised, will be pulled out of the press mold, thereby tending to cause damage to the lower edge of tile. On the other hand, the lower die will have to be raised by about $\frac{3}{16}$ in. to $\frac{5}{16}$ in. above the press mold and then allow it to lower until it rests on a catch which holds the lower die in its raised position flush with the press mold so that the pressed tile may be pushed off. This mode of operation results in several grave disadvantages. Through the lower die falling upon the aforesaid catch, a certain amount of tiles will be broken; through failure of the said catch, the lower die may fall through, thus resulting in double filling; owing to deposition of dust matter, the lower die might jam in its raised position above the mold surface, in which case it would be seized by the filling slide, thus causing fracture of the latter.

It is the object of this invention to avoid these and further disadvantages by introducing a positive and mechanically operated motion for the tile lifting and filling means, and by designing the latter in a manner to be hereinafter described.

According to the present invention, these two devices receive their motion from the ram which carries the upper die and which, by means of vertical tie rods guided by the press table, carries within the pedestal a cross beam which is provided both with driving elements for operating the lifter rod carrying the lower die and with a vertical tooth rack which imparts the required reciprocating motion to the horizontally guided filling slide by means of a gear mechanism and a rocking lever. Through this arrangement, the various movements can be exactly synchronized in the desired fashion while the individual parts may be designed in a simple, robust and dustproof manner.

According to the invention, the lifter rod is composed of an upper and a lower part which are screwed together thus forming a separable connection. Upon loosening of the screw connection, the rod can easily be dismantled by extracting the upper part through the press table and the lower part through the pedestal, so that the pit ordinarily required for the known types of press may be dispensed with.

The lifting elements for the lifter rod consist of an upper and a lower pair of tilting levers which are separably connected with each other and which are jointly pivoted on a single fulcrum member arranged parallel to

2

the cross beam. The upper pair of tilting levers is provided with cam faces which are acted upon by rollers mounted on the cross beam and constituting the driving elements for the levers, while the lower pair of tilting levers engages the lifter rod through a driver vertically adjustable on the rod.

The pairs of tilting levers are in engagement by means of clutches provided on their pivot pin, the upper levers being slideable on the pivot pin in axial direction against the action of springs, and a vertically adjustable wedge being provided on the cross beam which, while lifter rod and lower die are in their uppermost position, will at the proper moment force apart the levers of the upper pair with the aid of rollers provided on the levers, thus disengaging the clutches and releasing the levers of the lower pair that support the lifter rod.

In the upward travel the cross beam through its rollers causes the pairs of tilting levers to swing to such an extent that the lower levers will lift the lifter rod together with the lower die to such a degree that the latter is brought into alignment with the face of the molding frame. When the ram together with the cross beam suspended from it continues the upward movement, the rollers mounted on the cross beam slide on the faces of the upper levers in such a manner that the lower die will be mechanically held exactly level with the press mold surface until the pressed tile has been pushed off and the filling grate of the filling slide is positioned exactly above the lower die. At this point the aforesaid control wedge will force apart the upper pair of pivoted levers and disengage the clutch, thus releasing the lower pairs of levers and allowing the lower die together with the lifter rod to relapse into its initial position.

Through vertical adjustment of a front plate that carries the pivot pin of the tilting levers, the lifting device may be easily adapted from outside to any alteration of the filling space of the press mold, thus dispensing with the tedious adjustment that had hitherto to be made inside the pedestal.

The casing for the gear mechanism of the filling device which is actuated by the vertical tooth rack mounted on the cross beam of the ram, is screwed to the rear side of the pedestal in a manner to be vertically adjustable. It is fastened to the lower end of a vertically adjustable post passing through the table and carries, together with a support provided on the gear casing, the filling device. Through this arrangement, an accurate and speedy vertical adjustment of the filling device, and in particular of the filling slide, in respect to the press mold will be ensured.

The present invention furthermore provides between the filling slide and the gear mechanism a clutch which is automatically disengaged when the ram is moved beyond its regular uppermost position, this being necessary whenever the press elements have to be cleaned and when replacements or repairs are to be made. On disengaging the clutch, the filling slide can be withdrawn by hand from the press. When restarting the press, the clutch is automatically re-engaged irrespective of the position in which the filling slide may find itself.

The drawings illustrate a preferred embodiment of a tile press provided with lifting and filling means according to this invention.

Fig. 1 shows the lower portion of such a press, partly in view and partly in section.

Fig. 2 is a section of the lower portion of the press at right angles to Fig. 1, showing also the filling means and its gear mechanism as well as the lifting means.

Fig. 2a is a view of a detail in various working positions.

Fig. 3 is a bottom view of the gear mechanism as seen in the direction of the arrow III of Fig. 2.

Fig. 4 is a section along the line IV—IV of Fig. 2.

The ram 1 is vertically guided in the press frame 2 and carries the upper die 3. Attached to the ram 1 are two tie rods 4 which are guided by and pass through the press table 5 into the pedestal 6, where they carry a cross beam 7.

The cross beam 7 is guided within the pedestal 6 on adjustable rails 8 and is preferably provided with four pairs of rollers 9 running on the said rails.

10 is the press mold in which slides the lower die 11 which is mounted at the upper end of the lifter rod 12, which is guided by a central bush 13 of table 5 and by a bush located in the cross beam 7. The lifter rod consists of an upper part 12a and a lower part 12b. The two parts of the lifter rod are provided with a bore containing a screw 14 which is screwed with its upper end into the upper part 12a and by its head 14 and a holding plate 15 supports the lower part 12b. The two parts of the rod, 12a and 12b, are held together by the said screw 14.

The lower part 12b of the lifter rod 12 carries on a threaded portion an adjustable nut 16 which is provided with two rollers 17 and serves as a driver for the lifter rod.

The lifting motion of the lifter rod is produced by two rollers 19 which are pivoted by means of pins 18 in the cross beam 7 and press against oblique faces 21 of an upper pair of tilting levers 20, which in turn act on a lower pair of tilting levers 22 which engage nut 16 and through same raise the lifter rod 12 together with the lower die 11. The faces 21 also serve to hold the lifter rod 12 in its uppermost position with the lower die 11 in alignment with the face of the press mold 10. This is attained by the rollers 19 on the cross beam 7 sliding during the further upward travel of the cross beam along the faces 21, as illustrated in Fig. 2a, thus maintaining the die 11 level with the mold surface until the filling slide has pushed off the pressed tile while conveying fresh filling material onto the lower die.

The upper and lower pairs of tilting levers 20 and 22 are pivotably mounted on a fulcrum member 23 in a front plate 24 and their hubs form a clutch 25. Two springs 26 surrounding the pin 23 serve to keep the clutch in engagement. The upper levers 20 furthermore carry two oppositely disposed rollers 27 cooperating with a wedge 28. The wedge 28 is fastened in a vertically adjustable fashion by means of an angle 29 to the cross beam 7. At the moment when the filling slide is, together with the filling material, positioned above the lower die 11, the wedge 28 by way of the rollers 27 presses the upper levers 20 apart so as to disengage the clutch 25, thereby releasing the lower levers 22 and allowing the lifter rod 12 and the die 11, as well as the filling material carried by the latter, to fall down. During the subsequent pressing operation, the ram 1 will in its downward travel and by means of the cross beam 7 convey the aforesaid lifting elements back into their initial position. Buffer springs 30 limit the tilting movement of the levers 20 and 22 so that the members of the clutch 25 will always be in the proper engaging position.

For varying the thickness of the tiles to be pressed, in which case the die 11 has to be raised to a corresponding higher or lower level, front plate 24 supporting the lever pairs 20, 22 is vertically adjusted from outside by means of set screws (not shown).

The cross beam 7 has fastened to its rear side a vertical tooth rack 37 transmitting the up-and-down movement of the ram at the proper ratio to the filling device. The filling device consists of the horizontally reciprocating filling slide 38 which at every forward stroke conveys the requisite quantity of material for the press mold 10 out of a supply hopper 39. The slide 38 moves on a base 40 serving as guide track. This part 40 is supported at the front by a post 41 which is guided vertically by key and slot in the table 5 and may be vertically adjusted by means of a rack 42 and pinion 43. To the

lower end of the post 41, a casing 44 is fastened which encloses the gear mechanism transmitting the motion from the tooth rack 37 of the ram 7 to the filling slide 38. The casing 44 is bolted to the rear side of the press pedestal 6. It carries a bracket 45 which serves to support the rear end of the base 40 of the filling device. By adjusting the post 41, the filling slide together with the gear casing 44 may be set in exact relation to the press mold 10.

The length of stroke of the filling slide is much greater than that of the ram. If the latter amounts for instance to 4 in., the length of stroke of the filling slide will be 13.6 in. Accordingly, the gear ratio required for the transmission of motion will have to be 1 to 3.4. In the embodiment illustrated the gearing is composed of four gear wheels 46, 47, 48 and 49 which are contained in the casing 44. The first gear wheel 46 engages the tooth rack 37 through recesses in the casing 44 and the pedestal 6. The last gear wheel is mounted loose on its shaft 50 which carries outside the casing 44 two rocking levers 51 that are connected by means of guide rods 52 with hangers 53 on the filling slide 38.

If the pressing elements are to be cleaned or repaired, the space between the press mold face and the ram being in its normal uppermost position will not suffice. Moreover, while the ram is in this elevated position, the filling slide will be positioned above the press mold. In this case, the ram will have to be raised beyond its normal uppermost position and the slide must be withdrawn from the press mold. To this end, a clutch 54 has been provided between the shaft 50, to the ends of which the rocking levers 51 are fastened, and the gear wheel 49 that is mounted loose on the shaft 50. This clutch 54 through spring pressure normally couples the shaft 50 rigidly with the gear wheel 49. This clutch 54 is in engagement with one end of a disengaging lever 55, the other end of which is under the action of a cam disc 56 which is rigidly connected with the gear wheel 48.

If the ram 1 is raised for the above-mentioned reason beyond its top position, the corresponding gear mechanism 46-49 disengages the clutch 54 by way of the cam disc 56 and the lever 55, thus releasing the shaft 50 together with the rocking levers 51, so that the filling slide 38 may be withdrawn from the press. Sufficient space has now been created to claim to clean or repair the pressing elements, or even to replace the lifter rod 12, the upper part of which will be removed through the table in an upward direction as hereinbefore stated. Upon completion of the cleaning and repair work and upon restarting the press, the ram will on returning into its normal position cause re-engagement of the clutch 54 by way of the gear mechanism and the cam disc 56, thereby reestablishing the driving connection between the ram and the filling slide, no matter in which position the slide may find itself at this stage. Through this positive arrangement, contact between the ram and the filling slide will be excluded, too, so that breakage or damage cannot occur in this direction.

While with the former types of press the base of the filling slide consists of wheel guide rails screwed to the press frame, the base 40, according to the invention, is designed as a compact cast frame incorporating V guides 57 of the ball bearing V-way type, while the filling slide 38 is itself provided with corresponding inverted V's 58.

The fly-mass impetus of the filling slide 38 in its return movement is absorbed by adjustable buffers 59 mounted in the bracket 45 as well as by two buffers 60 mounted at the rear end of the slide.

This specific mode of actuating the filling slide from the ram over the gear mechanism, the favorable bearing of the filling slide on ball V ways, as well as the compensation of the filling slide impact by means of buffers, render the operation of the filling slide smooth, silent, and free from jerkiness, thereby substantially increasing

the potential working speed and, ultimately, raising the output.

The operation of the press is as follows: By power means, not shown, the ram 1 with the upper die 3 is vertically reciprocated with predetermined strokes and all movements of the tile lifting means and of the filling means are derived from the said reciprocating movement of the ram through the mechanisms described and shown. During the pressing of a tile the lower die 11 assumes its lowermost position in the mold and the upper die 3 acts on the mass in the mold, the ram being at the lower limit of its downward stroke. The filling slide 38 is at this moment in its rearmost position (Fig. 2). After the pressing the ram begins its upward stroke and in this movement takes along with it the lifting rod 12 with the die 11 so that the die lifts the tile out of the mould. When the die comes to lie flush with the top surface of the mold, it is held in this position and its further upward movement is interrupted while the ram continues its upward travel causing thereby the filling slide to be shifted forward. In this shifting movement the slide pushes off the ejected tile and when its grate filled with the mass to be pressed is above the mold, the lifter rod 12 with the die 11 is released and drops into its lower initial position, while at the same time the mass to be pressed falls into the mold. The movement of the ram is now reversed and it begins its downward stroke. In the first phase of this downward movement the filling slide recedes to its outermost position and the ram with the upper die in the continued downward travel performs the pressing of the tile in the mold 10, whereupon a new cycle begins.

What we claim is:

1. An automatic tile press comprising in combination a mold, an upper die carried by a vertically reciprocating ram, a lower die seated on a lifter rod, a horizontally reciprocating filling slide, and lifting elements for the lifter rod, a pair of spaced parallel tie rods fastened to and extending from the ram through the press table into the press pedestal and carrying therein a cross beam, means on this cross beam for operating the lifting elements of the lifter rod and a vertical tooth rack on the cross beam in operative engagement with a toothed gearing adapted to actuate rocking levers connected with the filling slide for imparting the required horizontal reciprocating movement to the same; said lifting elements for the lifter rod including an upper and lower pair of tilting levers which are jointly and pivotally mounted on a single fulcrum member arranged parallel to the said cross beam, the upper pair of levers being provided

with cam faces which are in contact with rollers that are mounted on the cross beam and constitute the driving element for the said levers, and the lower pair of levers engaging a vertically adjustable driver mounted on the lifter rod, said pairs of tilting levers being in engagement on their pivot pins by means of clutches, with the upper levers being slideable on the pivot pins in an axial direction, and the cross beam being provided with a vertically adjustable wedge which is adapted to cooperate with rollers on the levers of the upper pair for forcing these levers apart when the lifter rod with the lower die is in its top position and thereby disengage the clutches between the upper and lower levers and release the latter from their lifter rod supporting position.

2. A tile press as claimed in claim 1, in which the pivot pins of the tilting levers are mounted in a vertically adjustable front plate on the press pedestal.

3. An automatic tile press comprising in combination a mold, an upper die carried by a vertically reciprocating ram, a lower die seated on a lifter rod, a horizontally reciprocating filling slide, and lifting elements for the lifter rod, a pair of spaced parallel tie rods fastened to and extending from the ram through the press table into the press pedestal and carrying therein a cross beam, means on this cross beam for operating the lifting elements of the lifter rod, and a vertical tooth rack on the cross beam in operative engagement with a toothed gearing adapted to actuate rocking levers connected with the filling slide for imparting the required horizontal reciprocating movement to the same, said rocking levers which actuate the filling slide being mounted on the shaft of the last gear wheel of the said toothed gearing, and a clutch between said last mentioned gear wheel and the said rocking levers, said clutch being adapted to be automatically disengaged by a cam disk connected with that gear wheel of the toothed gearing which meshes with the last gear wheel.
